Primary Examiner — Alison M Ofstun*Assistant Examiner* — Evin F Ershock(74) *Attorney, Agent, or Firm* — Heedong Chae; Lucem, PC(57) **CLAIM**

The ornamental design for a cosmetic brush cover as shown and described.

DESCRIPTION

FIG. 1 is a perspective view of a cosmetic brush cover showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view thereof, shown in a first state of use, with a brush inserted, the brush being environmental subject matter; and,

FIG. 9 is a front view thereof, shown in a second state of use, with a second larger brush inserted, the brush being environmental subject matter.

The broken lines in the figures illustrates environment, and forms no part of the claimed design.

1 Claim, 6 Drawing Sheets(56)
